UNITED STATES PATENT OFFICE.

EMIL S. LUETH, OF BARABOO, AND CHARLES D. KNIGHT, OF MILWAUKEE, WISCONSIN, ASSIGNORS TO NATIONAL ELECTRIC COMPANY, OF MILWAUKEE, WISCONSIN, A CORPORATION OF WISCONSIN.

BRUSH-HOLDER.

SPECIFICATION forming part of Letters Patent No. 762,074, dated June 7, 1904.

Application filed March 21, 1904. Serial No. 199,122. (No model.)

To all whom it may concern:

Be it known that we, EMIL S. LUETH, residing at Baraboo, in the county of Sauk, and CHARLES D. KNIGHT, residing at Milwaukee, 5 in the county of Milwaukee, State of Wisconsin, citizens of the United States, have invented certain new and useful Improvements in Brush-Holders, of which the following is a specification, reference being had to the accompanying drawings, forming a part thereof.

This invention relates more particularly to devices for adjusting the springs by which the brushes are held against the commutators of electric motors or generators. Its main 15 objects are to facilitate the adjustment of the tension-spring and to provide for very slight variations in tension.

It consists in certain novel features of construction and in the peculiar arrangement of 20 parts hereinafter particularly described and claimed.

In the accompanying drawings like letters designate the same parts in the several figures.

25 Figure 1 is a longitudinal section on the line 1 1, Fig. 2, of a brush-holder embodying our invention. Fig. 2 is a partial plan view and a partial section on the line 2 2, Fig. 1. Fig. 3 is a side elevation of a part of the brush-holder, showing the spring-adjusting device; and Fig. 4 is a side elevation and section of a slightly-modified form of the brush-holder.

The body of the holder consists of a metal case or sleeve *a*, open at the ends and formed 35 on one side with a split collar *b* and on the opposite side with ears *c*. The brush-carbon *d* is fitted to slide freely endwise in the sleeve or case *a*. The collar *b* is provided with a clamping-screw *e*, by means of which it is adjustably secured on a stud *f* in the usual way. 40 A forked arm *g* is pivoted at its forked end between the ears *c* on a partially-split pin *h*, which projects at its ends through and is adapted to turn in holes in said ears. At its free 45 end the arm *g* is adapted to bear against the outer end of the brush *d*.

i is a spring coiled around the pin *h*, in

which it is inserted at one end and bearing at the other end against the arm *g*.

j is an arm, preferably of bail shape, engaged at the ends with the protruding ends of the pin *h*, one of which is squared, as shown in Figs. 2 and 3, to prevent it from turning therein.

k is a knurled eccentric or friction-grip 55 eccentrically journaled or pivoted between the branches of the arm *j* on a pin parallel with the pin *h*. The ears *c* are rounded concentrically with the pin *h* and are knurled on their edges to provide a more secure hold for 60 the eccentric or grip *k*.

The arm *g* may be dispensed with and the spring *i* made to bear directly at one end against the brush *d*, as shown in Fig. 4. The other end of the spring is secured in the split 65 pin *h*, and its tension is adjusted by a bail-shaped arm carrying an eccentric or eccentrically-pivoted friction-grip *k*, as shown in the other figures and hereinbefore described.

To adjust the tension of the spring in either 70 case, the eccentric or grip *k* is turned by the thumb and finger of the operator out of engagement with the knurled edges of the ears *c*. The arm *j* is then swung up or down to increase or diminish the tension and is secured 75 in the desired position by turning the eccentric or grip back into engagement with the ears *c*. The eccentric or grip is released from the ears *c* by slightly lifting the arm *j*. When it is engaged with said ears to lock the arm 80 in position, its bite against the knurled edges of the ears *c* is tightened by the force of the spring, tending to swing the arm *j* downward.

Various changes in details of construction, 85 particularly as to those parts of the holder which do not affect the tension device, may be made without departing from the principle and intended scope of our invention.

We claim—

1. In a brush-holder the combination with the body in which the brush is adapted to move endwise, a tension-spring for holding 90 the brush with yielding pressure against the

commutator, a pin to which one end of the spring is attached journaled in a projection on said body, an arm secured to said pin, and a friction-grip eccentrically pivoted to said arm 5 and adapted to be engaged with said projection, substantially as described.

2. In a brush-holder the combination with the body of the holder in which the brush is movable endwise, of a pin journaled in said body, a spring for holding the brush with yielding pressure against the commutator, coiled around and attached at one end to said pin, an arm secured to said pin, and a friction-grip adjustably pivoted to said arm and 10 15 adapted to be engaged at different points with a curved face on said holder, concentric with said pin, substantially as described.

3. In a brush-holder the combination with the body of the holder in which the brush is movable endwise and which is formed with semicircular ears, a pin journaled in said ears concentric with their curved edges, a tension-spring attached at one end to said pin between said ears, a bail-shaped arm engaged 20 25 with the ends of said pin, and a friction-grip eccentrically pivoted between the branches of said arm parallel with said pin and adapted to be turned into and out of engagement with the curved edges of said ears, substantially as de- 30 scribed.

4. In a brush-holder the combination with the body of the holder having a pair of rounded ears on one side, a pin journaled in said ears, a forked arm pivoted at its forked end be- 35 tween said ears on said pin, a spring attached

at one end to said pin and bearing at the other against said arm, an arm attached to said pin and a friction-grip eccentrically pivoted to the second arm and adapted to be turned into and out of engagement with the curved edges 40 of said ears, substantially as described.

5. In a brush-holder the combination with the body of the holder having an open-ended case or sleeve in which the brush is movable endwise, and a pair of perforated ears with 45 curved edges concentric with the perforations, a split pin passing loosely through the perforations in said ears, a forked arm loosely pivoted at its forked end on said pin between said ears and adapted to bear at its other end 50 against the outer end of the brush, a spring coiled around said pin and secured at one end therein and bearing at the other end against said arm, a bail-shaped arm engaged with the ends of said pin outside of said ears, and a friction-grip eccentrically pivoted between the branches of the second arm in position to be turned into and out of engagement with the adjacent edges of said ears, substantially 55 as described. 60

In witness whereof we hereto affix our signatures each in presence of two witnesses.
